UNITED STATES PATENT OFFICE.

EDMUND O. SCHWEIZER, OF CHICAGO, ILLINOIS.

GAUZE BRUSH.

1,228,484.

Specification of Letters Patent. Patented June 5, 1917.

Application filed March 17, 1916. Serial No. 84,778.

To all whom it may concern:

Be it known that I, EDMUND O. SCHWEIZER, a citizen of the United States, residing at Chicago, in the county of Cook and State of Illinois, have invented a certain new and useful Improvement in Gauze Brushes, of which the following is a full, clear, concise, and exact description, reference being had to the accompanying drawings, forming a 10 part of this specification.

This invention relates to brushes for electrical machinery, more particularly to the class of brushes formed of wire gauze, or the like.

15 The successful operation of rotating electrical machinery is predicated upon proper electrical contact being maintained between a stationary terminal, such as a brush and a moving terminal or surface such as a commutator or a collector ring or the like. The matter of maintaining an electrical conducting connection between the relatively stationary brush and the relatively moving collector ring, commutator or the like, is 20 spoken of broadly as commutation.

25 When this problem of commutation first arose in the early dynamo-electric machines, solid spring metal brushes were employed. This type of brush was soon found to be unsatisfactory as unevenness and irregularity 30 of the commutating surface prevented the maintenance of an even bearing or contact. The solid brush was found to lose much of its bearing area upon the slightest imperfection either in the moving surface or in the stationary brush. This loss of bearing area also occurred upon the slightest change 35 of position of the brush. Another marked difficulty was the arcing and heating that 40 attended the use of the old solid metal brush. This was due to the current flowing in the short circuited coils whose segments were under the brush.

45 Numerous expedients for securing a greater flexibility of the material of the brush and for securing a greater transverse resistance were tried. Various schemes of laminating the brush were proposed to get rid of the heavy short circuit current by increasing the transverse resistance of the 50 brush and to obtain a more nearly constant bearing surface.

55 Early in the art it was proposed to employ a brush made of wire gauze wound together and rolled or crushed into shape.

Such brushes were found to be quite generally satisfactory in that they had a relatively yielding bearing surface, a relatively low longitudinal resistance and a relatively high transverse resistance. They were also 60 easy and inexpensive to manufacture and maintain.

These brushes, as they were first constructed, were considered objectional for higher speed and for certain classes of commutation because of the excessive wear of 65 the commutator that their use entails. This excessive wear was due to the fact that the individual wires were relatively loose with respect to each other and the insulating segments of the commutator tended constantly to shift the position of the ends of the wires and sharp edges were constantly presented. Sharp edge tended to score the surface, and as a result, the wear upon the commutator 70 was found to be excessive. Where the gauze was made of a softer metal, it was found that the brush wore away rapidly. The wire gauze brushes when they were first employed were used in swinging brush 75 holders with the brush set at an angle to the radius of the commutator and the brushes were thus subject to bowing. The end of the brush also spread out or frayed as the brush became worn.

80 As soon as the short circuit effect in the commutator was intelligently comprehended, rigid carbon brushes were proposed. At about the same time there arose a requirement for reversibility of the rotor element and due to this requirement, as well as to the fact that molded carbon has no appreciable strength in tension and is relatively fragile, the practice of mounting the carbon brushes radially became prevalent.

85 With the advent of what is known as modern high speed or heavy duty machinery, it became necessary to commutate much greater quantities of current and greater current densities at increased peripheral speed. The poor heat conducting and low electrical conducting qualities of the carbon brush became a limiting factor.

90 The high current output required greater commutator area and this increased the frictional losses and especially in compact machinery of the modern turbine type the heating became prohibitive. As a result the modern type of semi-metallic or "carbon 95 alloy" brushes were developed, but they are 100 105 110

expensive to manufacture and require careful seating upon the commutating surface, due to their rigidity. The increased conductivity in a transverse direction also entails difficulty from short circuit current.

But through all these developments, the gauze brush, that is a brush made of woven wire screen or cloth has been extensively employed. This brush still persists in use for many classes of services in spite of the many new types of brushes, such as the Bronskol, Metite, metalloid, etc., which are made of a composition of graphite, carbon, copper, tin, etc., which are combined into a solid to form an alloy-like material.

The reason that the gauze brushes continue to be employed for the collection of current from commutators and collector rings is because they embody a large number of desirable qualities, such as relatively long life, relatively high carrying capacity, high transverse resistance, etc.

The gauze brush also causes less abrasion than the ordinary copper leaf brush unless the latter has been formed very expertly to the surface of the commutator or collector ring from which the current is collected.

Gauze brushes usually are made by rolling the gauze in sheets upon a suitable mandrel or arbor mounted in a machine adapted for the purpose. After the screen has been wound upon the mandrel to the desired dimension, the gauze is removed from the mandrel and is pressed in a suitable die to the desired form and dimension. One end is then usually soldered to hold the gauze in a permanent form. The electrical performance of gauze brushes can be made superior to that of the previously described brushes for heavy current service. However, with respect to mechanical performance, the gauze brush has failed to compete successfully with the more recently developed carbon, graphite, metal combination of brushes, such as are known by the trade names of Bronskol, Bronzeohl, Metite and similar material. This shortcoming lies in the fact that the gauze brush will cut the commutator or collector rings excessively or will itself be excessively worn by the abrasion of those surfaces.

My invention aims to provide a gauze brush which is so constructed that the abrasive tendency is greatly reduced, if not entirely eliminated, so that less wear, both upon the brush itself and upon the commutating surface is entailed.

The manner in which I practise my invention will now be set forth in detail, particular reference being made to the appended drawings which form a part of the present specification.

Figure 1 is an isometric view of one form of completed brush constructed in accordance with my invention;

Fig. 2 shows in elevation the wire gauze material from which the body of the brush is constructed;

Fig. 3 shows this material on an enlarged scale in cross section;

Fig. 4 shows a piece of the wire gauze upon which a deposit of other metal has been made, as will be described later;

Fig. 5 is a section similar to Fig. 3 showing the gauze after the deposition of metal thereupon;

Fig. 6 shows the manner in which the gauze is rolled upon a mandrel;

Fig. 7 illustrates in elevation the rollers which form the brush;

Fig. 8 illustrates a mandrel for obtaining a different size of brush;

Fig. 9 is a diagram illustrating the electro deposition of the metal upon the brush after the same has been formed.

Fig. 10 shows the manner in which the lubricating metal may be deposited by dipping in molten metal;

Fig. 11 shows in cross section the construction of a modified form of brush;

Fig. 12 illustrates the same in the completed condition; and

Figs. 13 and 14 are diagrams illustrating the action of an individual thread or wire upon which the lubricating metal is deposited.

According to my invention a suitable lubricating metal such as tin, lead and tin, Monel metal, or the like is deposited upon the wire screen in such a manner as to enclose each individual wire with a film or envelop of greater or less thickness of anti-friction metal.

The completed brush is preferably formed in the conventional prismatic form as shown in Fig. 1 to be employed in the different types of brush holders. A strip of copper, bronze or brass wire gauze, such as is illustrated in Fig. 2, is employed as the body of the brush. The brush may be formed and the anti-friction metal deposited upon the gauze after forming, or if preferred, the anti-friction metal may be deposited upon the gauze before the same is formed into brush form. Assuming that the first procedure is to be followed, a strip of the gauze 2 is wound upon a suitable mandrel 3 until a roll of the required size has been formed. The mandrel 3 is then withdrawn and the roll of gauze is then formed either by pressing in dies, or as shown in Fig. 6, by rolling between opposite pairs of rollers 4 and 5 to bring the brush to the required form.

The body of the brush 1 may then have the anti-friction metal deposited in the interstices of the gauze either by electroplating, as shown in Fig. 9, or by dipping, as shown in Fig. 10. The advantage of electroplating is that any desired amount of metal may be deposited. In other words,

the quantity control of the deposit renders it possible to determine to a nicety the thickness of the film deposited upon the gauze.

5 For electropolating the brush 1 forms the cathode in a suitable electrolyte 6, the anode 7 comprising the metal which is to be deposited upon the gauze of the brush 1.

If the anti-friction metal is to be deposited by dipping, a suitable bath of molten metal is prepared and the brush is dipped into the same and is then either shaken or centrififed or otherwise suitably treated to remove the excess of metal.

15 It is not essential that the gauze be first formed into a brush and the anti-friction metal then deposited thereupon, as I have found that the gauze may first be treated by electro-plating or by dipping, and the 20 gauze then rolled into suitable shape for forming the brush.

In Fig. 4 I have shown a piece of gauze upon the end of which 9, a deposit of anti-friction metal has been made. In Fig. 5 I 25 have shown a cross sectional view of the same. It can be seen that each individual wire 10 is surrounded by a film or coat of anti-friction metal 11. The brush may be formed in the same manner as previously 30 described, that is by rolling upon a mandrel and then forming either by dies or by rollers.

Special forms of brushes may be formed as shown in Fig. 8 where the mandrel 3 35 comprises a plate 12 for obtaining a flat roll of the gauze 2.

Where a large bearing surface is required, I have found it advantageous to 40 subdivide the gauze brush into a number of different parts. In this condition, the brushes can be more easily impregnated and can be formed more readily and cheaply because the size of the gauze sheet is less and manipulation is easier.

45 A gauze brush of excellent performance can also be made by constructing the same of a unit consisting of smaller units, as described, and then holding the units as shown at 13 in Fig. 11 together by means 50 of a sheet of gauze 14 wrapped one or more times around the aggregate units 13. The units 13 are formed in the usual way and the gauze wrapper 14 after being applied is pinned to retain it in position. The end 55 of the brush, as shown at 15 in Fig. 12, is dipped in hard solder to secure the parts together. The body of the brush may then be electro-plated.

If the anti-friction metal is to be deposited by dipping, hard soldering of the end 60 may be dispensed with or may be performed after the dipping operation.

The anti-friction metal which surrounds the individual wires operate to decrease the 65 friction of the contact surface by surround-

ing the cutting edges of the harder bronze or brass gauze wires 10 which form the body of the brush.

Assume that an individual wire such as 70 10 shown in Fig. 13 becomes adjusted to the commutator 16 and that thereafter the position of this wire is shifted as shown in Fig. 14. If the coating of anti-friction metal were not present the heel of the wire would present a fairly sharp surface and 75 would tend to score the commutator. However, the film of lubricating metal 11 prevents the sharp edge from coming directly in contact with the commutator 16.

The deposited anti-friction or lubricating 80 metal is also beneficial in increasing the effective cross section and consequently the carrying capacity for electric current without increasing the external dimension of the brush. A further advantage of this treatment lies in the fact that the gauze brush thus treated tends to hold its form permanently and will not bow or fray out at the edge of the contact surface as is the case with the gauze brushes of the prior art.

I prefer to use the electro-plating method 85 of applying the lubricating metal, although dipping the gauze in molten tin or the like has advantages in case a quick deposit of a maximum quantity of lubricating material is desired. Where dipping is employed, I 90 have found it advisable afterward to manipulate the brush so that the particles of impregnating metal will be somewhat disintegrated thus restoring the natural resiliency and flexibility of the gauze brush.

It is obvious that this principle of lubrication of the individual conductors will 95 apply to copper leaf brushes or the like.

It is apparent that I may treat the individual wires prior to weaving or fabricating them into gauze. I intend the following claims to cover the method of making the same as well as to cover a brush made of such material. The wires need not be 100 formed into a gauze but may be otherwise interlaced or bound together.

What I claim is:

1. In a brush of the class described, a contact wire adapted to rest on a commutator, 115 said wire being coated with an individual coating rigidly adhering to and moving with the wire and being made of a lubricating material softer than the metal of the wire, said lubricating coating being adapted to interpose itself between the commutator and the edge of the wire and to hold the wire out of direct contact with the commutator when the relative setting of the wire with respect to the commutator is shifted.

2. A brush for electrical machinery comprising a plurality of fine wires woven into a gauze, said wires being made of a metal comprising mostly copper, each of said wires having deposited thereupon an individual 120 125 130

- surface coating of a soft lubricating metal in solid form completely inclosing the wire, said coating adhering to and moving with the individual wire upon which it is deposited, said lubricating metal being substantially softer than copper.
3. A brush for dynamos and the like comprising a gauze body portion formed of interlacing wires, said wires having deposited upon their individual surfaces a surface film of soft crystalline lubricating metal, said metal being substantially softer than copper, said brush being substantially free of carbonaceous lubricating material.
- 10 4. A brush for electrical machinery comprising a body of wire gauze formed into a prismatic block, the wires of said gauze having deposited upon their individual surfaces individual surface coatings of a soft lubricating metal comprising tin.
- 15 5. A brush for electrical machinery comprising a body of wire gauze, the wire of said gauze being made of copper or an alloy thereof, the individual wires of said gauze having deposited upon their surfaces solid metallic surface films of a lubricating metal softer than copper, said films adhering to and moving with the individual wires.
- 20 6. A brush for electrical machinery comprising a plurality of sections formed of metallic wire gauze rolled and compressed into a prismatic form, a wrapper of metallic wire gauze surrounding said sections and means to hold said wrapper and said sections together, said sections and said wrapper having a surface deposit of a soft lubricating metal formed upon the individual wires thereof, said metal being substantially softer than copper.
- 25 7. The process of treating wire gauze employed for commutator or collector brushes which consists in depositing upon the individual wires a surface coating of tin in solid form.
- 30 8. The process of treating gauze employed for electrical brushes which consists in electrodepositing upon the individual wires of the gauze a surface coating of a soft metal consisting mostly of tin.
- 35 9. A brush for dynamos and the like comprising a body of gauze in compressed form, said gauze comprising a plurality of wires formed of a relatively hard metal consisting mainly of copper, each of said wires having deposited upon its surfaces a complete coating of tin forming a sheet of lubricating material adhering to and movable with the individual wire.
- 40 10. A brush for electrical machinery comprising a body of gauze, said body of gauze comprising a plurality of interlaced wires having upon their individual surfaces coatings only of a metal comprising tin, the interstices between said wires being open.
- 45 11. A brush for electrical contact with a metallic surface comprising a plurality of fine wires interwoven into a gauze, each of said wires having an individual coating thereon of metal softer than that of the wires and that of the contact surface whereby to provide a lubricating film between the wires and said surface.
- 50 12. A brush formed of interwoven metal wires having each an individual metal coating only of a metal softer than copper to afford lubricating means for the same.
- 55 In witness whereof, I hereunto subscribe my name this 15th day of March, A. D. 1916.
- 60 EDMUND O. SCHWEITZER.
